WHEEL REMOVING AND REPLACING APPARATUS

Joseph Edward Bailey, Jacksonville, Fla.

Application November 30, 1939, Serial No. 306,926

2 Claims. (Cl. 212—134)

This invention appertains to new and useful improvements in apparatus for conveniently removing and replacing the wheels on railroad rolling stock.

5 The principal object of the present invention is to provide an apparatus adapted to be employed for lifting the usual wheel truck bolster and lowering the same, and additional means for raising and lowering the truck sides so as to afford clearance to permit removal and insertion of the wedges and bearings and the adjustments incident thereto.

Another important object of the invention is to provide an apparatus of the character stated 15 which can be conveniently operated and which in operation will be efficient and foolproof.

Other objects and advantages of the invention will become apparent to the reader of the following specification.

20 In the drawings:

Figure 1 represents a front elevational view of the apparatus.

Figure 2 is a top plan view.

Figure 3 is an end elevational view.

25 Figure 4 is a cross-section on the line 4—4 of Figure 1.

Figure 5 is a section on the line 5—5 of Figure 2.

30 Figure 6 is a side elevational view of the bolster hook and block unit.

Referring to the drawings, wherein like numerals designate like parts, it can be seen in Figure 1 that numerals 5—5 represent the usual trackway rails on which the wheels 6 of a truck 35 generally referred to by numeral 1 can roll, this truck including the bolster 8 having the sides 9 and the journal boxes are denoted by numeral 10.

In carrying out the present invention, an elongated bar 11 of T-shape in cross section has up- 40 standing plates 12 at the ends thereof through which the elongated tie rod 13 has its ends disposed. Nuts 14 are provided on the ends of the rod 13 and these nuts can be screwed against the plate 12 for tightening intermediate portions of the rod 13 against the upper post portions of the bridge members 15, as is clearly shown in Figure 3. These bridge members 15 connect the upper portions of the legs 16. The bridge members are of substantially inverted U-shape, the upper portions of the leg members being diverged 45 downwardly as at a—a and then downwardly in parallel relation as at b—b, each portion b being provided with a base member 17. Connecting members 18 are provided between the leg portions a—a. The inverted U-shaped bridge mem-

bers 15 are filled by web plates 19 through which the bar 11 is disposed (see Fig. 5).

At an intermediate portion of the bar 11 is the bolster lifting block and fall generally referred to by numeral 20. On each end of the bar 11 is a 5 block and fall assembly 21.

Each of the block and fall assemblies consists of a Y-shaped upper portion bridged by a roller 23 riding on the portion of the bar 11 between the adjacent plate 12 and the nearest leg assembly. A cage 24 depends from the lower portion of the frame 22 and has the pulley 25 mounted therein. The assembly 21 also consists of the lower frame 26 having the pulleys 27 mounted therein and the chain arrangement 28 is trained over the pulleys 25 and 27 in the manner of a typical block and fall arrangement. However, the lower frame 26 has a depending leg 29 to which the hook 30 is pivotally connected and this hook is adapted to have several laps of chain 31 disposed over the same and under the upper bar of the corresponding side of the truck as suggested in Figure 1.

The block and fall 20 consists of the upper frame 32 having a hook 33 which is disposed through an opening 34 in the intermediate portion of the bar 11. This frame 32 has the pulleys 35 mounted therein and the usual block and fall chain arrangement 36 is interposed between the pulleys 36 and the pulleys 37 on the lower frame 38. This lower frame is shown in Figure 6 and includes the depending leg members 39 between which the swingable hooks 40—40 are mounted.

The hooks 40—40 are engageable against opposite sides of the bolster 8 to the end that when 35 the block and fall is operated the bolster can be lifted.

The assembly 20 is employed to raise the bolster and lower it, while the two side assemblies 21—21 are used to raise the truck side to afford 40 clearance to permit the removal of the wedges and bearings and subsequently the truck sides are removable from the journal by moving the assemblies 21 outwardly. After the truck sides have been removed they can be lowered to the 45 ground with the falls holding them upright so no dust nor dirt can be applied after the wheels are changed from old to new. Thus the journals are protected against foreign matters as well as scratching, by reason of engagement against the 50 ground or other structure.

While the foregoing specification sets forth the invention in specific terms, it is to be understood that numerous changes in the shape, size and materials may be resorted to without departing from 55

the spirit and scope of the invention as claimed hereinafter.

Having described the invention, what is claimed as new is:

- 5 1. A wheel removing and replacing apparatus comprising a frame, a bolster lifting assembly at the intermediate portion of the frame and longitudinally movable truck side handling assemblies at the ends of the frame, said frame consisting of a pair of leg units, each leg unit consisting of a pair of legs and a bridge member connecting the upper portions thereof, a bar extending horizontally and under the said bridge members, and a tie rod disposed longitudinally of the bar and over 10 the said bridge members and having its ends secured to the ends of the bar.
- 15

2. A wheel removing and replacing apparatus comprising a frame, a bolster lifting assembly at the intermediate portion of the frame and longitudinally movable truck side handling assemblies at the ends of the frame, said frame consisting of a pair of leg units, each leg unit consisting of a pair of legs and a bridge member connecting the upper portions thereof, a bar extending horizontally and under the said bridge members, and a tie rod disposed longitudinally of the bar and over 5 the said bridge members and having its ends secured to the ends of the bar, said bar being of angle iron construction, said side handling assemblies being provided with roller mounts rideable on the said flanged bar.

JOSEPH EDWARD BAILEY.
